DRIVE MECHANISM FOR TRENCH DIGGING MACHINE

Adolph F. Laue, Elmore, Minn.

Application August 11, 1954; Serial No. 449,228

7 Claims. (Cl. 37—86)

This invention relates to improvements in ditching machines and has for its primary object the provision of an improved winch drive assembly for effecting the desired rise or pitch in a ditch or trench being dug.

Another object of this invention is to provide an improved winch drive assembly for ditching machines which, unlike conventional structures, will effect a steady and continuous movement of the machine whereby a smooth ditch bottom and a uniform rise in the ditch or trench being dug is obtained.

Still another object of this invention is to provide improvements in the winch drive mechanisms for ditching machines wherein change feed mechanism is interposed within the drive of the winch such that variations in the speed of the ditching machine may be obtained while the speed of the conveyor carrying the ditch cutters is unaltered, thus adapting the machine to varying soil conditions.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a side elevational view of a ditching machine constructed in accordance with this invention;

Figure 2 is a horizontal section showing the lower portion of the main assembly and the manner of interconnection between the main frame and the trenching boom;

Figure 3 is an enlarged fragmentary vertical section taken substantially along the plane of section line 3—3 in Figure 2;

Figure 4 is a transverse vertical section taken substantially along the plane of section line 4—4 in Figure 3;

Figure 5 is a perspective view showing one end portion of a trenching boom; and

Figure 6 is a diagrammatic perspective view of the improved winch and drive mechanism therefor.

Referring now more particularly to the drawings, the trenching machine will be seen to consist of a main frame assembly indicated generally by the reference character 10 incorporating a pair of lower side frame members 12 and 14 and a pair of upper side frame members 16 and 18. The various side frame members are rigidly interconnected at their rearward ends by a pair of vertical guide members 20 and 22 which support in turn an upper cross piece member 24 having depending wheel mount frame members 26 and 28 depending from its opposite ends which carry suitable spindles for journaling the wheels 30 and 32. The various side frame members are of course rigidly interconnected by suitable brace means throughout their length and it will be noted that the lower pair of side frame members 12 and 14 project forwardly beyond the other side frame members and are provided therewith a tongue member 34 such that the ditching machine is readily attached

2

to a tractor assembly indicated generally by the reference character 35.

As will be seen most clearly in Figure 2, a drive shaft member 36 is journaled transversely between the side frame members 12 and 14 by means of suitable bearing members 38 and 40 mounted thereon and attached to one of the side frame members 12, one end portion extending into a gear housing assembly 42 by means of which the drive shaft 36 is drivingly connected with a power take-off connector shaft 44 extending forwardly from the gear housing and connected through a suitable flexible coupling element 46 to the power take-off shaft extension member 48 carried by the tractor 35.

A sprocket member 50 is rigidly secured to the drive shaft 36 intermediate the side frame members 12 and 14 and on opposite sides of this sprocket are provided sleeve members 52 and 54 which serve to space the boom assembly indicated generally by reference character 56 in properly spaced relation to the side frame members 12 and 14; the boom incorporating, as shown most clearly in Figure 5, an elongated boom member 58 preferably of channel or box section and having its forward end cut away in the manner shown such that spaced legs 60 and 62 are presented for straddling the sprocket 50 such that the apertures 64 in these legs are pivotally received on the drive shaft 36.

Adjacent its rearward end the boom member 58 is provided with a rectangular framework assembly 66 which has opposite side pieces 68 and 70 adapted to be positioned closely adjacent the opposed surfaces of the guide members 20 and 22, previously mentioned, to prevent lateral swing of the boom assembly. The boom assembly is rigidified by the provision of a pair of truss-like stringer assemblies 72 and 74 and, as will be readily apparent, the rearward end of the boom assembly carries a sprocket member 76 and is provided intermediate its ends with a depending idler sprocket member 78 in a manner shown most clearly in Figure 1. An endless flexible chain element 80 is trained about the sprockets 50, 76 and 78 and this chain carries a plurality of various shaped cutting elements 82 for performing a ditching or trenching operation.

The ditcher also includes a manually controlled winding drum member 84 mounted on the member 24 above the boom and a cable 86 is wound about this drum and is dead ended as at 88 to the boom assembly. The winding drum includes a worm wheel member 90 engaged by a worm 92 at the rearward end of a crank member 94 which extends forwardly to terminate in a region of the tractor 35 such that the operator of the tractor may manipulate the handle portion 96 of the crank assembly to operate the winding drum 84 and raise or lower the boom assembly as desired.

The above described assembly is entirely conventional in nature and forms no part of this invention. Ordinarily, ditchers of the type above described utilize a winch assembly for operating the cable 104 which is actuated by means of a ratchet mechanism to effect a step by step winding of an anchor cable thereon. In operation of conventional machines the anchor cable is payed out for a distance of say 100 feet and firmly secured to any suitable object which will not move as the machine is advanced. The tractor is used only for the purpose of deriving the power take-off drive therefrom and no motive power is applied to its wheels when the unit is operated. The rise of the ditch is controlled by the operator by manipulating the crank 96. However, the ditch which results from operation of conventional machines leaves something to be desired in the way of evenness of the ditch inasmuch as the aforementioned ratchet mechanism imparts a step by step advance of the machine which causes the ditcher to dip at the moment the advance

starts and a consequent raising of the rearward end of the ditching boom. As soon as the ratchet mechanism releases the pull on the anchor cable, the rearward end of the machine will settle. This constant up and down motion of the rear end of the ditcher boom results in a very uneven ditch bottom, requiring considerable hand smoothing operations if the tile is to be laid in the ditch with any degree of accuracy. To overcome this objectional feature and to effect a continuous and steady raising of the boom assembly during the ditching operation, the winch assembly shown most clearly in Figure 6 is utilized.

To overcome this objectionable feature of conventional ditchers, the winch assembly will be seen to consist of a transmission unit 106 rigidly mounted between the upper side frame members 16 and 18 of the main frame and which includes an input shaft member 108 and an output shaft 110. The free end of the input shaft 108 is provided with a sprocket member 112 and a corresponding end of the drive shaft 36 is provided with a sprocket 114 such that the chain member 116 trained about these two sprockets will impart rotation to the input shaft 108. The output shaft 110 is connected by means of a suitable universal joint 118 to a stub shaft 120 which carries a sprocket 122 at its free end. Journaled between the upper side frame members on the main frame assembly forwardly of the input and output shafts of the transmission is a lay shaft member 124 having sprockets 126 and 128 at its opposite ends in a manner shown. A chain member 130 is trained about the sprockets 122 and 126 and a chain member 132 is trained about the sprocket 128 and a sprocket 134 fixed to one end of the winch shaft 136 which is journaled between the lower side frame members as shown. The winch shaft has a winding drum member 138 rigid therewith and about which the previously mentioned cable 104 is wound.

In operation of the machine, the shifting lever 140 of the transmission unit is disposed in neutral position and the machine is placed at that point where it is desired to obtain the lowest point of trenching. With the tractor transmission in neutral, the power take-off extension shaft 48 is operated to rotate the drive shaft 36 and therefore effect movement of the ditching chain. Thereafter, the crank member 94 is manipulated to progressively lower the boom assembly into the ground until the desired ultimate depth of ditch is obtained. At this point, the transmission unit 106 is engaged in one of its several gear ratios depending upon the condition of the soil so that the desired forward speed of the machine and the tractor is obtained. During the forward motion of the tractor and operation of the ditching chain assembly, the winding drum 138 will be slowly rotated to take up on the cable 104 and thereby slowly and evenly advance the machine and tractor, permitting the operator to obtain a smooth and even ditch bottom.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly all suitable modifications and equivalents may be resorted to, falling within the scope of the appended claims.

What is claimed as new is as follows:

1. In a ditching machine having a wheeled main frame assembly including a pair of spaced side members, a drive shaft journaled transversely of and between said side members, an elongated boom pivotally received at one end on said drive shaft, a power take-off connector shaft on said frame drivingly connected to one end of said drive shaft, a change speed transmission unit mounted on said main frame above said drive shaft and including input and output shafts, means carried on said frame drivingly connecting said drive shaft and said input shaft,

a winch shaft journaled on said main frame and having a winding drum secured thereon, means carried on said frame drivingly connecting said transmission output shaft and said winch shaft, and a cable wound upon said drum for imparting forward motion to said machine.

2. In a ditching machine having a wheeled main frame assembly including a pair of spaced side members, a drive shaft journaled transversely of and between said side members, an elongated boom pivotally received at one end on said drive shaft, a power take-off connector shaft on said frame drivingly connected to one end of said drive shaft, a change speed transmission unit mounted on said main frame above said drive shaft and including input and output shafts, means carried on said frame drivingly connecting said drive shaft and said input shaft, a winch shaft journaled on said main frame and having a winding drum secured thereon, a lay shaft journaled on said main frame in spaced relation to the output shaft of said transmission, means carried on said frame drivingly connecting said output shaft and said lay shaft, means carried on said frame drivingly connecting said lay shaft and said winch shaft, and a cable wound upon said drum for imparting forward motion to said machine.

3. In a ditching machine having a wheeled main frame assembly including a pair of spaced side members, a drive shaft journaled transversely of and between said side members, an elongated boom pivotally received at one end on said drive shaft, a power take-off connector shaft on said frame drivingly connected to one end of said drive shaft, a sprocket fixed to the other end of said drive shaft, a change speed transmission unit mounted on said main frame above said drive shaft and including an input shaft and an output shaft, a sprocket on said input shaft, a chain trained about the input and drive shaft sprockets drivingly connecting the same, a winch shaft journaled on said main frame and having a winding drum secured thereon, means carried on said frame drivingly connecting said transmission output shaft and said winch shaft, and a cable wound upon said drum for imparting forward motion to said machine.

4. In a ditching machine having a wheeled main frame assembly including a pair of spaced side members, a drive shaft journaled transversely of and between said side members, an elongated boom pivotally received at one end on said drive shaft, a power take-off connector shaft on said frame drivingly connected to one end of said drive shaft, a sprocket fixed to the other end of said drive shaft, a change speed transmission unit mounted on said main frame above said drive shaft and including an input shaft and an output shaft, a sprocket on said input shaft, a chain trained about the input and drive shaft sprockets drivingly connecting the same, a lay shaft journaled on said main frame in spaced relation to the output shaft of said transmission, means carried on said frame drivingly connecting said output shaft and said lay shaft, a winch shaft journaled on said main frame and having a winding drum secured thereto, means carried on said frame drivingly connecting said lay shaft and said winch shaft, and a cable wound upon said drum for imparting forward motion to said machine.

5. In a ditching machine having a wheeled main frame assembly including a pair of spaced side members, a drive shaft journaled transversely of and between said side members, an elongated boom pivotally received at one end on said drive shaft, a power take-off connector shaft on said frame drivingly connected to one end of said drive shaft, a sprocket fixed to the other end of said drive shaft, a change speed transmission unit mounted on said main frame above said drive shaft and including an input shaft and an output shaft, a sprocket on said input shaft, a chain trained about the input and drive shaft sprockets drivingly connecting the same, a winch shaft journaled on said main frame and having a winding drum secured thereon, means carried on said frame including a flexible chain drivingly connecting said trans-

mission output shaft and said winch shaft, and a cable wound upon said drum for imparting forward motion to said machine.

6. In a ditching machine having a wheeled main frame assembly including a pair of spaced side members, a drive shaft journaled transversely of and between said side members, an elongated boom pivotally received at one end on said drive shaft, a power take-off connector shaft on said frame drivingly connected to one end of said drive shaft, a sprocket fixed to the other end of said drive shaft, a change speed transmission unit mounted on said main frame above said drive shaft and including input and output shafts, means carried on said frame drivingly connecting said drive shaft and said input shaft, a winch shaft journaled on said main frame and having a winding drum secured thereon, a lay shaft journaled on said main frame in spaced relation to the output shaft of said transmission, a chain drivingly connected between said output and lay shafts, a chain drivingly connected between said lay and winch shafts, and a cable wound upon said drum for imparting forward motion to said machine.

7. In a ditching machine having a wheeled main frame assembly including a pair of spaced side members, a

drive shaft journaled transversely of and between said side members, an elongated boom pivotally received at one end on said drive shaft, a power take-off connector shaft on said frame drivingly connected to one end of said drive shaft, a sprocket fixed to the other end of said drive shaft, a change speed transmission unit mounted on said main frame above said drive shaft and including an input shaft and an output shaft, a sprocket on said input shaft, a chain trained about the input and drive shaft sprockets drivingly connecting the same, a lay shaft journaled on said main frame in spaced relation to the output shaft of said transmission, a chain drivingly connecting said output and lay shafts, a winch shaft journaled on said main frame and having a winding drum secured thereon, a chain drivingly connecting said lay and winch shafts, and a cable wound upon said drum for imparting forward motion to said machine.
